AUTOMATIC STOP DEVICE FOR SEWING MACHINES

Walter A. Behrens, Jamaica, N. Y., assignor to
Pathé Tool Manufacturing Co., Inc., Long Island
City, N. Y., a corporation of New York

Application October 28, 1944, Serial No. 560,861

7 Claims. (Cl. 112—219)

This invention generally relates to sewing machines and more particularly to means for automatically stopping the operation of power driven quilting machines in the event of failure of a thread.

Devices of this character controlled by the threads are known in the art, but they are not entirely satisfactory for various reasons, such as comparative complication and high cost of manufacture, relative unreliability, and lack of compactness of elements of the structure, that renders such devices particularly unsatisfactory for use with sewing machines employing a considerable number of needles in which the automatic stopping of the motor, upon failure of any one of the numerous threads, is of special importance due to the difficulty of immediately detecting such a failure.

The present invention permits to overcome the shortcomings of the devices of the prior art and is specifically directed to the provision of novel means controlled by the tensioning of the threads in a predetermined phase of the stitching cycle and operative to stop the motor of the sewing machine whenever any one of the threads fails to be tensioned due to the breaking thereof or other causes. One object of the invention is to provide means of the aforementioned character adapted to be most advantageously employed in multi-needle sewing machines and embodying thread controlled contact units that are simple and inexpensive to manufacture and small and compact in construction, so as to be easily arranged to form rows of closely spaced units adapted for association with a number of needle threads fed through the machine in close proximity to each other.

Another object of the invention is to provide a thread-controlled automatic stop device, as aforementioned, comprising contact units dependable in operation, which are concealed within a supporting structure and are protected against dust so as to substantially eliminate any possibility of failure of the device.

Since in multi-needle sewing machines, use of all the needles is not always required, it is a further object of the invention to provide thread-controlled contact units of the character described that may be selectively and rapidly rendered inoperative, by merely rotating the same through a fixed angle to an "off" position.

These and other objects will become apparent in the following description of the invention illustrated in the drawings, wherein:

Fig. 1 is an end elevational view of associated

elements, including a "bottom bar assembly," of a sewing machine embodying an automatic stop device according to the invention.

Fig. 2 is an exploded view illustrating the various elements forming the bottom bar assembly.

Fig. 3 is an enlarged front elevational view of a portion of the bottom bar assembly comprising a pair of contact units according to the invention, one of which has been rendered inoperative.

Fig. 4 is a vertical section on line 4—4 of Fig. 3, in the direction of the arrows, illustrating the position of an operative contact unit when the thread associated therewith is tensioned.

Fig. 5 is a similar vertical section illustrating the position of the contact unit when its thread is not tensioned.

Fig. 6 is a vertical section, on line 6—6 of Fig. 3, through an inoperative contact unit.

Fig. 7 is a diagrammatical illustration of the electric connections of the device.

Referring now in detail to the drawings and particularly to Figs. 1 and 2, numeral 10 generally indicates a structure comprising a suitably supported stationary bar 11, an insulating member or block 12, a contact element or strip 13 and a plurality of contact units 14 through which the threads pass. Said structure is located underneath an oscillating "take-up" bar 16 and a fixed bar 17 provided with the usual tension devices 18 for insuring uniform feed of the threads, and will be hereafter designated as "bottom bar assembly" by reason of the position of the aforementioned stationary bar 11.

As illustrated in Fig. 1, each of the needle threads 19 is first passed through one of the eyelets 20 and one of the tension devices 18 of the fixed bar 17, is then led downwardly and through one of the contact units 14 of the bottom bar assembly, thence upwardly to one of eyelets 21 of the take-up bar 16 and finally downwardly again to a sewing needle 22. As will be apparent, the oscillating take-up bar 16 will therefore, once during the stitching cycle, tension all the threads in use in the machine and cause the threads to exert an upward pull on the respective contact units 14 through which they pass, for the purpose and with the results to be later described.

With the exception of the bottom bar assembly 10, which will be hereafter described more in detail, the aforementioned elements are conventional and only so much of the structure thereof has been shown in the drawings as is required to illustrate the relation thereto of the bottom

bar assembly 10 and to permit a complete understanding of the invention.

The stationary bar 11 is grooved to provide therein a plurality of recesses 23 uniformly spaced from each other, a bore 24 extending upwardly from each of said recesses to receive one end of a coil spring 25. Within the recesses 23 there are mounted the contact units 14, which are vertically and rotatably movable therein. Each of the contact units consists of a body formed of a porcelain eyelet 26 and a pair of brass eyelets or grommets 27, 28, assembled on the porcelain eyelet and having flanges that extend in juxtaposition to opposed faces of the bar 11 to prevent lateral displacement of the contact units relative to the bar. (See Figs. 4 and 5.) The flange of the grommet 28 is cut to define straight edges 30, 31, at a right angle to one another, the function whereof will become later apparent.

Secured to the underside of the stationary bar 11, as by means of screws 32, is the aforementioned insulating block 12, of "Bakelite" or like material, which is offset relative to the bar to provide a projecting portion or ledge underneath the flanges of the grommets 28. The contact strip or element 13, preferably made of brass, is secured to the block 12, as by means of screws 34, opposite the projecting portion of the block, and is provided with spaced projections or bosses 36 alined with the contact units 14, inwardly of the flanges of the grommets 27.

The contact units 14 are normally disposed in the bar 11 with the edge 30 of the flange of their grommets 28 parallel to the upper face of the ledge formed by the block 12. In such an angular position of the contact units (operative or "on" position, which may be suitably marked thereon, See Fig. 3) the spring 25 of each contact unit is effective to displace the unit downwardly and to maintain the grommet 27 thereof in surface engagement with the respective boss 36 of the contact strip 13 alined therewith, as shown in Fig. 4, provided the thread 19 passing through the porcelain eyelet 26 of the unit is slack. Upon tensioning of the thread, following the operation of the take-up bar once during each stitching cycle, as aforementioned, the unit 14 will be pulled upwardly away from the associated boss 36 of the contact strip 13, to the position illustrated in Fig. 4. Failure of any one of the threads to displace the respective unit 14 at the instant of the take-up, will result in stopping the motor which drives the machine, in the manner that will now be described.

As illustrated in Fig. 7, the power circuit of the electric motor 40 of the sewing machine comprises normally closed switches 42, which may be opened to shut off the motor by a solenoid 43. This latter forms part of an open electric circuit, suitably connected to the motor power circuit, which also includes a switch 44 and a vacuum tube relay 45 for energizing the solenoid 43, and which is bridged by the contact strip 13 and contact units 14 when these latter are in the strip-contacting position shown in Fig. 5. Normally, during operation of the machine, the threads are not under tension, and the contact units 14 are therefore in the aforementioned position, but the switch 44 is open so that no current flows to the relay 45.

A shaft 46 driven from the motor 40 through suitable speed-reducing transmission, carries a cam 47 acting to close the switch 44 once during each stitching cycle at the instant in which the

take-up bar 16 is operated to tension the threads 19. At that moment, therefore, all the contact units 14 are displaced upwardly to the position of Fig. 4, and consequently no current will flow to the relay 45 notwithstanding the closing of the switch 44, so that the operation of the motor will not be interrupted.

Should, however, any of the threads be broken, or for any other reason not under tension at the instant of the take-up, the respective contact unit 14 will retain its strip-contacting position under the influence of its spring 25, and will bridge the circuit thereby permitting flow of current to the relay 45 and causing the solenoid 43 to be energized to open the motor circuit switches 42 and immediately shut off the motor.

Since in a multi-needle sewing machine certain of the needles may sometimes not be in use, and the contact units associated therewith would then not be controlled by the threads, it is apparent from the foregoing that such contact units must be rendered inoperative to prevent the same from stopping the machine in synchronism with the operation of the take-up bar.

For this purpose, it is sufficient to rotate any desired contact units through an angle of 90 degrees, to dispose the edge 31 of the flange of the grommet 28 thereof parallel to the upper face of the projecting portion of the insulating block 12. In such a position of the flange, the unit is prevented from moving into contact with the respective boss of the contact strip 13 by the abutment of the edge 31 on the insulating block 12, as shown in Fig. 6, and is therefore ineffective to bridge the circuit described at any time. Manifestly, the unit may readily be returned to its operative position through an inverse directional movement thereof.

It is to be understood that numerous changes and modifications may be made in the structure described and illustrated in the drawings without departing from the spirit of the invention or exceeding the scope of the claims.

I claim:

1. In a motor driven multi-needle sewing machine having means for tensioning the threads in a predetermined phase of each stitching cycle, a normally open electric circuit, means actuated upon closing of said circuit for stopping the motor, and means for controlling the closing of said circuit, said last mentioned means comprising a normally open switch periodically closed in synchronism with the tensioning of the threads and a plurality of contact units each associated with one of the threads, said units normally bridging the circuit and being periodically displaced by the tensioning of the threads from their circuit-bridging position simultaneously with the closing of said switch, the failure of a thread to be tensioned causing the respective contact unit to maintain its circuit-bridging position thereby permitting actuation of the means for stopping the motor.

2. In a motor driven multi-needle machine having means for tensioning the threads in a predetermined phase of each stitching cycle, a normally open electric circuit, a contact element connected in said circuit, a plurality of contact units each associated with one of the threads, said units being normally held in contact with said contact element to bridge said circuit and being displaceable by the tensioning of the threads from said normal position thereof, means effective upon closing of the circuit to stop the motor, means for closing the circuit in synchronism with the tensioning of the threads.

nism with the tensioning of the threads, the tensioning of the threads simultaneously causing the contact units to be displaced by the threads from said normal position thereof thereby normally preventing the actuation of the means for stopping the motor, the failure of any one of the threads to be tensioned causing the respective contact unit to maintain its normal circuit bridging position thereby permitting operation of the means for stopping the motor.

3. In a motor driven multi-needle sewing machine having means for tensioning the threads in a predetermined phase of each stitching cycle, a stationary bar, an insulating block and a contact element carried by said bar, a plurality of contact units movably mounted in said bar, each comprising a body through which one of the threads passes and a pair of metal eyelets mounted on said body one of which is maintained in contact with said contact element in the normal position of the unit, said units being displaceable by the tensioning of the threads from said normal position thereof, means effective at the instant of the tensioning of the threads to stop the motor whenever any one of said contact units maintains its normal position due to the failure of the respective thread to displace the same, each of said units being rotatable in said stationary bar and one of said metal eyelets of the unit having a flange adapted to engage in the rotation of the unit said aforementioned insulating block to lock the unit in a position wherein the aforementioned contact eyelet is prevented from contacting said contact element, whereby any one of the units may be selectively rendered inoperative.

4. In a motor driven multi-needle sewing machine comprising means for tensioning the threads in a predetermined phase of each stitching cycle, a normally open electric circuit including a switch periodically closed in synchronism with the tensioning of the threads and means for stopping the motor upon closing of said circuit, a device for controlling the closing of said circuit comprising a stationary supporting member, a fixed contact element associated with said member and connected in the circuit, a plurality of contact units movably mounted in the supporting member, and means for normally maintaining said units in contact with said fixed contact element to bridge the circuit, each of said units being associated with one of the threads and adapted to be displaced by the tensioning of the respective thread from its normal position, the failure of any one of the threads to be tensioned causing the associated contact unit to maintain its normal position thereby determining the closing of the circuit.

5. In a motor driven multi-needle sewing machine comprising means for tensioning the threads in a predetermined phase of each stitching cycle, a normally open electric circuit including a switch periodically closed in synchronism with the tensioning of the threads and means for stopping the motor upon closing of said circuit, a device for controlling the closing of said circuit comprising a stationary supporting member, a fixed contact element associated with said member and connected in the circuit, a plurality of contact units movably mounted in the sup-

porting member, and means for normally maintaining said units in contact with said fixed contact element to bridge the circuit, each of said units being associated with one of the threads and adapted to be displaced by the tensioning of the respective thread from its normal position, the failure of any one of the threads to be tensioned causing the associated contact unit to maintain its normal position thereby determining

5 the closing of the circuit, said contact units being rotatable in the supporting member to a position in which contact thereof with the fixed contact element is prevented at all times whereby any one of the units may be rendered selectively inoperative.

6. In a motor driven multi-needle sewing machine comprising means for tensioning the threads in a predetermined phase of each stitching cycle, a normally open electric circuit including a switch periodically closed simultaneously with the tensioning of the threads and means for stopping the motor upon closing of said circuit, a device for controlling the closing of said circuit comprising a stationary bar, a fixed contact element carried by said bar and connected in said circuit, a plurality of contact units movably mounted in said stationary bar, each comprising a body through which one of the threads passes and a member carried by said body adapted to bridge the circuit, and resilient means for normally maintaining said units in circuit-bridging position, each of said units being displaceable by the tensioning of the respective thread from its normal position and the failure of any one of the threads to be tensioned causing the associated contact unit to maintain its normal position thereby determining the closing of the circuit.

7. In a motor driven multi-needle sewing machine comprising take-up means for tensioning the threads in a predetermined phase of each stitching cycle, a normally open electric circuit including a switch periodically closed in synchronism with the tensioning of the threads and means for stopping the motor upon closing of said circuit, a device for controlling the closing of said circuit comprising a stationary support, an insulating block and a contact element connected in said circuit carried by said support, a

40 plurality of contact units movably mounted in said support, each comprising a body through which one of the threads passes and a member carried by said body adapted to contact said contact element to bridge the circuit, and resilient means mounted in the support for normally maintaining said units in circuit-bridging position, each of the units being displaceable by the tensioning of the respective thread from its normal position and the failure of any one of the threads to be tensioned causing the associated contact unit to maintain its normal position thereby determining the closing of the circuit, each unit being rotatable in the support to a position in which contact of the member carried by

45 the body of the unit with the contact element aforementioned is prevented at all times, whereby any one of the units may be rendered selectively inoperative.
